CENTRIFUGAL GOVERNOR WITH HYDRAULIC BOOSTER

Herman G. Adler, Detroit, Mich., assignor to Novi Equipment Company, Novi, Mich., a corporation of Michigan

Application April 23, 1951, Serial No. 222,336

10 Claims. (Cl. 121—43)

The present invention relates to an engine governor, and more particularly to a governor including centrifugal means responsive to speed of an engine in combination with a hydraulic motor such as a piston and cylinder for effecting control of the engine.

It is an object of the present invention to provide a simplified hydraulic governor in which the centrifugal unit, the actuating motor, and a valve for controlling the actuating motor in accordance with engine speed is compactly arranged in a simple casting so as to occupy a minimum of space and to permit fabrication of the units at a low cost.

It is a further object of the present invention to provide a hydraulic governor characterized by its ability to prevent substantially overshooting of speed under severe operating conditions.

It is a further object of the present invention to provide a novel arrangement of centrifugal governor, hydraulic valve actuated thereby, and hydraulic motor controlled by said valve.

Other objects and features of the invention will become apparent as the description proceeds, especially when taken in conjunction with the accompanying drawings, wherein:

Figure 1 is a plan view of a governor assembly constructed in accordance with the present invention.

Figure 2 is a section on the line 2—2, Figure 1.

Figure 3 is a sectional view similar to Figure 2 showing the unit under different operating conditions.

Figure 4 is a view similar to Figure 2 showing the unit under yet another different operating condition.

Figure 5 is a section on the line 5—5, Figure 2.

Figure 6 is a section on the line 6—6, Figure 1.

Figure 7 is a side elevation of the metering sleeve.

Described in general terms, the hydraulic governor comprises a main casting having an enlarged chamber at one side thereof communicating with a bore which extends from the chamber through to the opposite side of the casting. The casting is provided with an elongated power cylinder formed integrally therewith, which is closed at the same side of the casting as the chamber. The cylinder is open at the opposite end and is provided with a removable head. The head is apertured to provide for passage of a piston rod connected to mechanism for controlling the speed of the engine. The casting is provided with a passage connecting the closed end of the cylinder with the chamber and a spring is located between the closed end of the cylinder and the piston constantly biasing the piston toward the open end of the cylinder. A fluid passage is provided in the casting which intersects the bore and extends to the interior of the cylinder between the head of the cylinder and the piston. A centrifugal unit connected to be driven by the engine is located in the chamber and includes a shiftable part engaging a valve slidably mounted in the bore to control the passage of hydraulic fluid to the cylinder.

Referring now to the drawings, the governor comprises a main casting 10 provided with an enlarged chamber 12 at one side thereof. As shown in Figure 2, the cham-

2

ber is generally cylindrical at its outer portion and includes a conical inner portion 14. Communicating with the inner end of the conical portion 14 is a bore 16 extending to the opposite side of the casting 10. Closely adjacent and parallel to the chamber 12 and the bore 16 is a cylinder 18 which is closed at one end by a transverse wall 20 which is part of the casting. The upper end of the cylinder 18 is closed by a removable head 22 having a bore 24 therethrough slidably receiving a piston rod 26 connected at its inner end to a piston 28. Intermediate the transverse wall 20 of the cylinder and the piston 28 is a compression spring 30 constantly urging the piston upwardly, as seen in Figure 1.

Located within the casting 10 is a fluid passage comprising straight sections 32, 34, and 36. The passages 34 and 36 connect at opposite sides of the cylindrical bore 16. Another passage 38 is provided which connects the lower side of the cylinder 18 to the chamber 12.

Located principally within the chamber 12 is a centrifugal device comprising a rotary shaft 40 having a sleeve 42 pressed thereon, the sleeve 42 having a radially outwardly extending flange 44. Rotatably received on the shaft 40 and in abutment with the flange 44 is a ball race 46 herein shown as having a flat radially extending ball engaging surface 48. Rigidly secured to the shaft 40 is a driver 50 carrying a plurality of centrifugal balls 52. Rotatably and slidably mounted on the shaft 40 is a second ball race 54 having a conically disposed ball engaging surface 56. It will be apparent that as the balls 52 move outwardly under the influence of centrifugal force, the upper ball race 54 is moved axially of shaft 40 and upwardly thereon as illustrated in Figure 1.

Located within the cylindrical bore 16 of the casting 10 is a metering sleeve 60. The metering sleeve 60 has a port 62 in one side thereof in communication with the fluid passage 34. At its opposite side it is provided with a narrow notch or metering slot 64. Located axially beyond the metering sleeve 60 is a second valve sleeve 66 which is spaced from the metering sleeve 60 to provide an annular space therebetween. Preferably, the bore 16 of the casting is cylindrically recessed as indicated at 68 to provide an annular enlarged fluid passage. The metering slot 64 and the annular passage 68 are in communication through the fluid passage 36 to the upper end of the cylinder 18.

Slidably mounted in the metering sleeve 60 is a spool or shuttle valve 70 having an upper land 72, a lower land 74, and an elongated annular groove 76 intermediate said lands. The valve 70 intermediate its ends is provided with a transverse wall 78 having an opening 80 therethrough. Below the transverse wall 78 the valve 70 has one or more outlet ports 82 adapted to communicate with the interior of the chamber 12.

The upper end of the bore 16 is closed by a removable plate 84 carrying an adjusting screw 86, the lower end of which is provided with a spring seat 88 engaging one end of a compression spring 90. The lower end of the compression spring 90 is seated against the upper surface of the transverse wall 78. Obviously, compression of the spring 90 may be varied by adjustment of the screw 86, and the screw is retained in adjusted position by a lock nut 92. The upper end of the screw and lock nut are covered and concealed by a removable threaded closure element 94.

Obviously, compression of the spring 90 acts to resist upward movement of the race 54 and accordingly the spring acts as a governor spring to determine the speed at which the governor controls the operation of the engine. The shaft 40 is connected to a rotating part of the engine in the usual manner.

The piston rod 26 at its upper end carries a head 100 to which a rocker arm or lever 102 is pivoted inter-

mediate the ends thereof. To one free end of the rocker arm 102 there is provided a link 104 which extends to a foot pedal or other instrumentality under the control of the operator. The other end of the rocker lever 102 is connected by a link 106 to a speed control device on the engine such for example, as a carburetor valve. The linkage is connected such that upward movement of the link 106, as seen in Figure 2, results in opening movement of the valve or results in an increase in speed of the engine.

The removable head 22 is provided with a laterally and upwardly extending projection 110 recessed to receive an abutment pin 112 which limits movement of the rocker lever 102 in one direction as seen in Figure 3. Intermediate the head 100 of the piston rod 26 and the removable head 22 of the cylinder is a short relatively strong compression type buffer spring 114. This spring is engaged by the head 100 at a predetermined point in its downward movement, as seen in Figure 2, and operates to provide stability at or near no load.

The piston 28 is provided with an upwardly extending pin 116 received within a guide recess 118 provided within the cylinder.

A bypass passage 120 is provided which connects the fluid passage 36 with the interior of the chamber 12. The passage 120 is provided with means for variably restricting flow of fluid through the passage and this means is illustrated in detail in Figure 5. As seen in this figure the casting 10 is provided with a boss 122 which has a transverse opening 124 therein, the outer portion of which is internally threaded. Inwardly of its threaded portion the opening 124 is reduced in cross-section and intersects the passage 120. Located in the reduced portion of the opening 124 is a part 126 having a flat surface 128 providing for a flow of fluid from the upper portion of the passage 120 into the opening 124 beyond the open end of the part 126. The part 126 is provided with an axially extending opening 130 and a transverse opening 132 which communicates with the passage 120. Located within the threaded portion of the opening 120 is a metering valve 134 having a threaded head and provided with a metering point 136 which enters into the axial opening in the part 126. Accordingly, adjustment of the metering valve 134 adjusts the flow of fluid through the passage 120 by restricting the space between the point 136 and the end opening into the part 126. A compression spring 138 is interposed between the metering valve 134 and the part 126, and a closure nut 140 is provided for the opening 120.

The present device is intended to control the speed of an engine in such a way as to prevent excessive speeds when the throttle is fully opened under no load or under light load. One of the particular uses for which the unit was designed is a tank engine characterized by high power and an extremely light fly wheel. Accordingly, under no load the motor tends to accelerate to dangerous speeds extremely rapidly. It is a requirement that the governor operate to move the carburetor throttle from wide open to fully closed in a small fraction of a second.

At the same time substantial power is required to effect movement of the throttle valve or carburetor valve which is the reason the hydraulic motor in the form of a piston and cylinder device is employed. The desired results are accomplished by providing for actuation of the piston 28 in one direction by hydraulic fluid and effecting movement of the piston in the opposite direction by the compression spring 30. The side of the piston engaged by the compression spring 30 is subjected to atmospheric through the passage 38 to the chamber 12. Moreover, the valve is particularly designed so that as the upper limit of governed speed is exceeded, a massive substantially instantaneous flow of hydraulic fluid is introduced into the cylinder, so that the piston will be moved downwardly with extreme rapidity, thus closing the throttle or control valve of the engine.

The bypass passage 120 and its metering valve 134 permits adjustment of the operation of the valve and tends to smooth out the action of the unit.

Three different operating conditions are illustrated in Figures 2, 3 and 4. In Figure 2 an operating condition is illustrated in which the engine is running dead idle. As illustrated in this figure the link 104 is in upper position and the governor is ineffective to control speed of the engine. At this time the ball race 54 is in its lowermost position and the valve 70 is held in its lowermost position by the governor spring 90. At this time it will be observed that the upper land 72 of the valve is below the bottom of the metering notch 64 and accordingly flow of fluid from the reduced portion of the valve 76 to the cylinder 18 is prevented. At the same time, there is a passage for fluid out of the cylinder which includes the passage 36, the interior of the hollow valve 70, the port 80 through the transverse wall of the valve, and the transverse ports 82 in the lower portion of the valve, thus permitting fluid to flow from the cylinder to the interior of the chamber 12.

In Figure 3 the parts are illustrated in operative or speed controlling position. At this time the foot pedal has been depressed to bring one arm of the rocker lever 102 into abutment with the pin 112. This has the effect of first opening the throttle as a result of corresponding movement of the link 106. As the engine speed increases the balls 52 move outwardly and move the upper race 54 upwardly, thus displacing valve 70 upwardly to a position where the upper land 72 opens a passage through the metering notch 64 permitting fluid under pressure to flow into the upper end of the cylinder and moving the piston 28 downwardly. At this time the foot pedal will be held depressed and the control action of the governor results in rocking movement of the lever 102 about the axis illustrated in Figure 3. In practice, the position illustrated in Figure 3 is that assumed when the engine is operating at about 2800 R. P. M. under full load.

In Figure 4 there is illustrated a condition which is reached when load is removed from the engine. Due to the removal of load, engine speed increases rapidly and the balls 52 move outwardly, thus moving ball race 54 upwardly. At some predetermined speed, as for example 2950 R. P. M., the lower edge of the land 72 reaches the upper end of the metering notch 64. If the governed speed of 2950 R. P. M. (for example) is exceeded, further upward movement of the valve 70 opens the annular port defined between the adjacent ends of the metering sleeve 60 and the upper sleeve 66. This provides, with a minimum of upward movement of the valve 70, a very large massive flow of hydraulic fluid, the passages and ports being designed so that a substantially unrestricted flow of fluid may take place in the valve through the cylinder. This results in almost instant downward movement of the piston 28 to its lowermost position where it abuts an embossment 142 provided at the bottom of the cylinder 18. The final downward movement of the piston 28 to the position shown in Figure 4 is opposed by the relatively strong compression spring 114.

In order to adjust the governor to operate at desired conditions, the first adjustment is made with the foot pedal fully depressed and with the engine operating under full load as illustrated in Figure 3. At this time screw 86 is adjusted to give a desired speed to the engine as for example in the example under consideration, 2800 R. P. M. Turning the screw in a direction to further compress the governor spring 90 increases the speed. The screw 86 should be adjusted so that under full load at 2800 R. P. M. the governor starts to close the carburetor valve. The second adjustment is made with the foot pedal fully depressed and with the engine operating at no load. Under these circumstances the metering valve 134 is adjusted inwardly until the engine speed is equal to 2950 R. P. M. Turning the screw in a direction to decrease the flow of

fluid through the bypass passage 120 has the effect of decreasing engine speed.

With the governor adjusted as above described, it will operate at full load at 2800 R. P. M. for example, and will govern the speed up to 2950 R. P. M. under no load conditions. Moreover, due to the design of the governor, and particularly to the arrangement for quick response upon exceeding the predetermined top limit of governed speed, substantial over-shooting is prevented even though the engine has inherently a very rapid acceleration. Moreover, the governor operates smoothly and without substantial surges to control the speed of the engine at intermediate speeds under intermediate loads.

Referring now to Figure 6, means are provided for locking the valve 70 in position during shipment of the governor. This means comprises a threaded opening 150 carrying a locking screw 152, the metering sleeve 60 being provided with an opening for the passage of a pin portion 154 carried by the screw 152. The pin portion 154 engages the valve 70 intermediate its lands 72 and 74 and prevents its separation from the assembly.

The metering sleeve 60 in the particular embodiment illustrated, comprises a cylindrical sleeve having a port 62 for communication with the passage 34. The metering notch 64 is herein shown as of rectangular cross-section and in the particular valve illustrated, has a width of about .026" and a depth of about .1175".

The entire unit is housed within a unitary casting, which forms a housing for the rotary elements, the control valve, and the power cylinder. The power cylinder is located parallel to and at the side of the chamber and communicating bore. The fluid passages are arranged such that they may be drilled in the casting. Thus passage 34 is in alignment with the open end of the bore 16 and is drilled therethrough. Fluid passage 36 is in alignment with the open end of cylinder 18 and is drilled therethrough. Fluid passages 38 and 120 are in alignment with the open end of chamber 12 and are drilled therethrough. Fluid passage 32 and opening 124 are drilled directly from exterior surfaces of the casting. By the defined arrangement, the unit is cheap and easy to make and in completed form represents a most efficient use of space.

The drawings and the foregoing specification constitute a description of the improved engine governor in such full, clear, concise and exact terms as to enable any person skilled in the art to practice the invention, the scope of which is indicated by the appended claims.

What I claim as my invention is:

1. Structure of the character described comprising a casting having an enlarged chamber open at one side thereof, a bore extending from said chamber to the other side of said body, a cylinder in said body at the side of said chamber and bore, said cylinder being open at the side of said body opposite said chamber and its opposite end being closed, a removable head for the open end of said cylinder including an abutment thereon, a piston in said cylinder, a piston rod extending from said piston through said head, a lever pivoted to the outer end of said rod and movable into engagement with said abutment, an operator control link connected to said lever, a governing link also connected to said lever for connection with a speed control element, centrifugal governing means in said chamber, a valve in said bore operably connected to said means, and a fluid passage in said body controlled by said valve for carrying fluid under pressure to said cylinder.

2. Structure as defined in claim 1 in which a passage is provided in said body connecting the closed end of said cylinder to said chamber.

3. Structure as defined in claim 2 comprising a compression spring between the closed end of said cylinder and said piston.

4. Structure as defined in claim 3 comprising a short compression spring operable during only a part of the

stroke of said piston to oppose movement of said piston toward the closed end of said cylinder.

5. In a governor of the character described, a casting having a large chamber open at one side thereof including an inner conical portion; a bore extending from the inner end of said conical portion and open at the other side of said casting; a power cylinder formed in said casting having a closed end at the said one side thereof and open at the said other side thereof; a first straight fluid passage extending into said casting adjacent a side of said chamber; a second straight fluid passage extending along the side of the conical portion of said chamber, communicating with said first passage, intersecting a side of said bore, and aligned with the open end of said bore; a third straight fluid passage extending into said bore at one end thereof, extending into said power cylinder at the other end thereof and in alignment with the open end of said power cylinder; a fourth straight fluid passage connecting the closed end of said power cylinder to said chamber, and in alignment with the open end of said chamber; and a fifth straight fluid passage connecting said third fluid passage to the interior of said chamber and in alignment with the open end of said casting.

6. In a governor of the character described, means for controlling supply and exhaust of pressure fluid to a fluid motor, comprising a body having a hollow cylindrical part opening at one end into a completely annular enlargement, the end of said part at said enlargement having a surface perpendicular to the axis of said part provided with a relatively narrow notch extending axially of said part from said surface, an inlet passage having an inlet port opening into said part intermediate the ends thereof, a supply passage opening into said enlargement, a valve having spaced annular lands spanning said inlet port and an intermediate reduced portion, the one of said lands adjacent said enlargement having at the end thereof adjacent said reduced portion an end surface perpendicular to the axis of said cylindrical part whereby movement of the said end surface of said one land over said notch provides for a restricted flow past said valve, and movement of the said end surface of said one land past the end surface of said cylindrical part provides for a greatly increased flow past said valve.

7. Structure as defined in claim 6 comprising a passage connecting said supply passage to exhaust, and an adjustable metering valve in said last recited passage to provide for a constant but restricted flow of fluid from said supply passage to exhaust when said valve is in position to connect said inlet and supply passages.

8. In a governor of the character described, a casting having a large chamber open at one side thereof including an inner conical portion; a bore extending from the inner end of said conical portion and open at the other side of said casting; a power cylinder formed in said casting having a closed end at the said one side thereof and open at the said other side thereof; a straight fluid inlet passage extending along the side of said conical portion of said chamber, intersecting a side of said bore, and aligned with the open end of said bore; a straight fluid supply passage connecting said bore and one end of said cylinder and aligned with the open end of said cylinder; a straight drain passage connecting the closed end of said cylinder and said chamber and aligned with the open side of said chamber; and another straight passage connecting said supply passage and said chamber and aligned with the open side of said chamber.

9. A governor comprising a unitary casting having a chamber extending upwardly from its bottom surface, said chamber having a lower cylindrical portion and an upper inwardly tapered conical portion, a bore extending from the upper end of said chamber to the upper surface of said casting, said casting having a vertical power cylinder formed therein parallel to and spaced laterally from said chamber, said cylinder being closed at its bottom and open at its top, a removable top closure for said

cylinder, a power piston in said cylinder having a piston rod extending through said closure, centrifugal means in said chamber, vertically movable valve means in said bore operatively connected to said centrifugal means and movable vertically thereby on increase in speed of said centrifugal means, a removable closure for the upper end of said bore, resilient means below said closure and effective to oppose vertical movement of said valve means in response to increase in speed of said centrifugal means, a fluid passage leading from the lower surface of said casting to said valve means and from said valve means to the upper end of said cylinder, a drain passage leading from the lower end of said cylinder to said chamber, and a bypass passage connecting said chamber to the portion of said first passage intermediate said valve means and said cylinder.

10. Structure of the character described comprising a casting having an enlarged chamber open at one side thereof, a bore extending from said chamber to the other side of said body, a cylinder in said body at the side of said chamber and bore, said cylinder being open at the side of said body opposite said chamber and its opposite end being closed, a removable head for the open end of said cylinder, a piston in said cylinder, a piston rod extending from said piston through said head, a lever pivoted to the outer end of said rod, said structure including a rigid abutment extending beyond said head, said lever being movable into engagement with said abutment by movement of said rod or by rocking movement on said rod, or by a combination of both, an operator control link connected to said lever, a governing link also con-

nected to said lever for connection with a speed control element, centrifugal governing means in said chamber, a valve in said bore operably connected to said means, and a fluid passage in said body controlled by said valve for carrying fluid under pressure to said cylinder.
